251-83

SR

FIP: 09/96

OR

AI00142

*M. Woodbury,
Globe Valve,
No 42, AI Patented May 6, 1856.*

Witnesses.

*J. Avery Richards
John L. Collyer*

Inventor.

Moses Woodbury.

M. Woodbury,

P.2

Globe Valve,

No. 142,

AI Patented May 6, 1856.

L is screw
end of screw L   T joint   P flange step receiver
N plug   S cylinder valve

Placing screw L with hollow cylindrical valve spring placed behind valve.

part 3 or valve body proper rises with extra pressure again allowing water to escape and pressure is reduced.